GRILLE OR SCREEN

Lemual G. Brown, P.O. Box 14488, Britton, Okla.
Filed June 18, 1964, Ser. No. 376,048
9 Claims. (Cl. 52—626)

This invention relates generally to an improved grille or screen for shading portions of a building. More particularly, but not by way of limitation, this invention relates to an improved grille or screen incorporating means for securely retaining and spacing the terminal ends of thin, elongated strips utilized in constructing such grilles or screens.

Many buildings constructed in recent years have a large percentage of the exterior surface constructed from glass, providing very large window areas for the building. These same buildings are generally completely air conditioned and, because of the presence of the large window areas, have tremendous heating loads due to the effect of solar energy passing therethrough. It has been found that the air condition load to cool a building can be substantially reduced by installing grilles or screens adjacent the exterior of the windows to prevent the direct passage of sunlight through the window. The screens generally utilize a latticework of thin, elongated strips canted at an angle to shade the building, thereby preventing the direct entrance of sunlight through the windows while at the same time maintaining a substantially uninterrupted view through the windows from the interior. Furthermore, air conditioning systems of the size utilized in cooling a large building require the use of a cooling tower which is located on the exterior of the building. It has been found that the use of grilles or screens of the type disclosed herein enhances the operation of the cooling tower and also presents a pleasing external appearance to the buildings. A grille structure of this general type is illustrated in Hallock United States Patent 3,004,642.

Generally, grilles heretofore provided are constructed from a plurality of thin, elongated strips, which may be continuous for the entire width of the grille or may be formed by connecting strip segments in end-to-end relation to provide the length desired. The elongated strips are fastened together and held in spaced relation by a plurality of clips which are positioned between the strips at regular intervals. The strips and clips combine to form a latticework structure, and generally define some form of opening through which air can pass. With most arrangements of strips and clips, the latticework portion of the grille may be quickly and easily assembled, but securing the terminal ends of the strips in proper spaced relation in some form of frame has presented a serious problem. For the most part, the terminal ends are bolted or screwed into a channel member by the use of various forms of brackets which are secured both to the strips and to the interior of the channel member. To secure the terminal ends of the strips by this method, a large number of holes must be either pre-punched in the channel member or drilled in the strips and channel members during assembly. Such a procedure is extremely time-consuming and difficult where an extremely large grille structure is to be installed on the side of a building.

This invention contemplates a grille structure of the general type described, but providing means for quickly and easily securing the terminal ends of the strips. In more specific terms, the terminal ends of the strips are provided with dovetailed grooves which are convergent toward the adjacent end edges of the respective strips. A frame member, which receives and covers the ends of the strips, is provided with a supporting member extending along the interior of the frame member and having divergent sides arranged to fit within the dovetailed grooves in the terminal ends of the strips to secure the

2

strips to the frame member. Spacer members, which have a web portion and a pair of convergent legs extending therefrom, are arranged to be slidably received by the support member. The spacer members are provided in suitable lengths to hold the strips in the proper spaced relation when assembled with the supporting member.

It is therefore one object of the invention to provide an improved grille construction which includes means for quickly and easily securing the terminal ends of the grille-forming strips in properly spaced relation.

Another object of the invention is to provide improved structure for securing the terminal ends of grille-forming strips, which structure does not require the use of fastening means such as bolts or screws.

Still another object of the invention is to provide an improved grille or screen which can be assembled for shading and protecting structural elements of buildings and the like.

A further object of the invention is to provide an improved grille which can be easily fabricated from extruded easily assembled, relative simple parts so that an ornamental effect may be produced.

Another object of the invention is to provide an improved grille formed of components which are easily stacked in a relatively small area for shipping and storage.

Still another object of the invention is to provide an improved grille which may be easily assembled and is sturdy and contains sufficient inherent rigidity to support its own weight and to resist heavy wind or air pressure without collapsing.

The foregoing and additional objects and advantages of the invention will become more apparent as the following description is read in conjunction with the accompanying drawings wherein like reference characters denote like parts in all views, and wherein:

FIG. 1 is a fragmented elevational view, partly in cross-section, of one embodiment of a grille constructed in accordance with the invention;

FIG. 2 is an exploded view of a portion of the grille of FIG. 1 illustrating the means for retaining the terminal ends of the grille-forming strips;

FIG. 3 is a vertical cross-sectional view of the grille of FIG. 1, taken substantially along the line 3—3 of FIG. 1;

FIG. 4 is a view of one embodiment of a clip which can be utilized in the grille of FIG. 1;

FIG. 5 is a perspective view of one embodiment of a grille-forming strip as it is utilized with the clip of FIG. 4;

FIG. 6 is a cross-sectional view, taken substantially along the line 6—6 of FIG. 5;

FIG. 7 is an end elevation view of another embodiment of a clip that can be utilized in forming a grille construction in accordance with the invention;

FIG. 8 is a side elevation view of another embodiment of a clip that can be utilized in forming a grille construction in accordance with the invention;

FIG. 9 is a perspective view of the clip of FIG. 8, illustrating the use in conjunction therewith of a continuous grille-forming strip; and,

FIG. 10 is a cross-sectional view, taken substantially along the line 10—10 of FIG. 9.

Referring to the drawings, and to FIG. 1 in particular, shown therein is a grille or screen constructed in accordance with the invention and generally designated by the reference numeral 12. As illustrated, the grille 12 includes a side frame member 14 connected with a bottom frame member 16. It should be understood that FIG. 1 is a fragmentary view showing only a portion of a complete grille 12, and that additional side, bottom and top members will be provided as required. The grille 12 also includes a plurality of relatively narrow, elongated strips

18 which extend transversely across the grille 12 and are held in spaced relation by a plurality of clips 20.

As shown more clearly in FIG. 2, the side frame members 14 are preferably in the form of a channel having a web portion 26 and a pair of legs 28 disposed at each end of the web portion 26 and extending inwardly toward the strips 18. In the preferred form of the side frame member 14, a support member or portion 30 extends longitudinally of the side frame member between the legs 28. The support member 30 provides a pair of surfaces 32 which are divergent from each other and from the web portion 26 of the side frame member 14, for purposes which will become more apparent as the description proceeds. It should be understood that the support member 30 may less preferably be in the form of a solid wedge-like member attached to the web 26 and having a pair of divergent surfaces as described. Also, as may be seen more clearly in FIG. 2, at least terminal ends 33 of the strips 18 are provided with dovetailed notches 34 defined by edges 36 and 38 which are convergent toward the terminal ends 33 of the strips 18. The dovetailed notch is sized to fit the support member 30, and the convergent slot edges 36 and 38 are arranged to slidably engage the divergent surfaces 32 of the support member 30 so that the strip 18 will be retained against longitudinal displacement from the side frame members 14.

The specific construction of spacer members 40 and 42, which are shown in FIG. 1, may be more clearly seen in FIG. 2. The spacer members 40 and 42 each include a web portion 44 and a pair of convergent legs 46 and 48 extending from opposite sides of the web portion 44. The spacer members 40 and 42 are sized to be slidably disposed over the support member 30 and when so disposed, the convergent legs 46 and 48 of the spacer members cooperate with the divergent surfaces 32 of the support member 30 to retain the spacer members thereon. Upper and lower surfaces 50 and 52, respectively, of the spacer members 40 and 42 are preferably disposed at an angle with respect to the longitudinal dimension of the support member 30 so that the strips 18 will be retained in the desired angular or canted position. It should be apparent from the foregoing description that the spacer members 40 and 42 are substantially identical in construction. The only structural distinction being in the length of the members, which will be determined by the desired spacing of the strips 18 to maintain the geometric pattern characteristic of the grille.

The elongated strips 18 may be constructed from flat, relatively thin material, such as plastic, aluminum, steel, etc. The strips 18, which extend in one continuous piece across the grille 12, comprise a plurality of offset, horizontally and vertically spaced, parallel portions 53 that are interconnected by inclined portions 55. As shown in FIG. 1, each strip 18 is inverted with respect to the preceding and following strip 18 to form, when assembled with the clips 20, a lattice structure having generally octagonal openings.

Assembly of the grille 12 as shown in FIG. 1 may be accomplished by installing the bottom frame member 16 and all or sections of the side frame members 14. A lower spacer member, which in the instance of FIG. 1 would be the long spacer member 40, is slipped over the support member 30 to a position adjacent the bottom frame member 16. A strip 18 is then placed with its dovetailed groove 34 over the support member 30 and lowered until the strip 18 is resting on the upper surface 50 of the spacer member 40. The short spacer member 42 is then inserted on the support member 30 and positioned adjacent the upper surface of the strip 18. A second strip 18, inverted with respect to the first strip 18, is then slipped onto the support member 30. The clips 20 are then fastened to the adjacent parallel portions 53 of the first and second strips 18. The foregoing procedure is repeated until the grille 12 has reached the desired height. From the foregoing it can be seen that no screws, bolts or other external fastening means is necessary to complete the as-

sembly of the grille 12, thereby reducing the time and the difficulty involved in assembling the grille.

The clip 20 illustrated in FIG. 1 is shown in more detail in FIG. 4. As shown therein, the clip 20 includes an end section A and an end section B. The end section A includes a bent web 54 having parallel legs 56 extending therefrom. Transverse lugs 58 and 60 are provided at the juncture between the legs 56 and the web 54. The lugs 58 and 60 are undercut to provide transversely extending grooves 62 for receiving one longitudinal edge of the strips 18. The free ends of the legs 56 are provided with transversely extending hook-shaped end portions 64, for purposes which will become more apparent hereinafter. The end section B of the clip 20 is provided with a similar bent web 68 and a pair of parallel legs 70 connected at the ends of the web 68. Transverse lugs 72 and 74 are located on the section B at the juncture between the web 68 and the legs 70. The lugs 72 and 74 are undercut to provide transverse grooves 76 for receiving the other longitudinal edge of a strip 18. The free ends of the legs 70 converge slightly toward each other and are provided with grooves 78 arranged to cooperably receive the hook-shaped end portions 64 of the legs 56, whereby the sections A and B are securely fastened together to form the clip 20.

When the sections A and B are joined in this fashion, it can be seen that the grooves 62 and 76 in lugs 58 and 72 are arranged to receive the opposed longitudinal edge portions of one strip 18, and the grooves 62 and 76 in lugs 60 and 74 are arranged to receive the opposed longitudinal edge portions of a second strip 18. When the grille is assembled, the strips 18 will be held in spaced relation by the clips 20. It can be appreciated from viewing FIG. 3 that as the strips 18 and appropriate spacer members 40 or 42 are placed in position in the side frame member 14, the sections A and B of the clip 20, which are separated prior to assembly, can be placed over the edges of the parallel portions 53 of the strips 18 and pressed together to cause the hook-shaped end portions 64 of the section A to engage the grooves 78 of section B.

The perspective view shown in FIG. 5 and the cross-sectional view shown in FIG. 6 illustrate an application of the clip 20 to one embodiment of the grille-forming strip which is designated by the reference character 118. The strip 118 is comprised of a plurality of segments 118a and 118b. The segment 118a includes parallel end portions 120 and 122 which are held in spaced relation both vertically and horizontally by means of a central portion 124. The segment 118b is identical to the segment 118a except that the end portions 120 and 122 are retained in reverse spaced relationship as compared with the ends 120 and 122 of the segment 118a. The end portion 120 is provided with a transversely extending groove 126 and the end portion 122 is provided with a transversely extending hook portion 128, which is arranged to cooperably engage the groove 126 to retain the segments 118a and 118b in an assembled position to form the strip 118.

As can be most clearly seen in FIG. 6, the end portion 122 and the end portion 120 are each provided with transversely extending beads 129 to retain the segments 118a and 118b in proper orientation as the edges thereof are inserted in the grooves 62-76 of the clip 20. It should also be pointed out that each end portion 120 and 122 of each of the segments 118a and 118b is provided with a dovetailed groove 130 (see FIG. 5). The dovetailed grooves 130 serve the same function as the dovetailed grooves 34 in the strip 18, as previously described. While it is not necessary to provide the dovetailed groove 130 in each end of the segments 118a and 118b, it is preferred to form the segments in this manner so that it will not be necessary to provide special end segments for joining the strip 118 to the side frame member 14. The advantage of the segmented strip 118 over the strip 18 is that substantially any width of grille 12 can be formed without the necessity of providing strips of special length. Also,

segments 118a and 118b may be stored and handled much easier than the continuous strips 18.

The clip embodiment shown in FIG. 7 is generally designated by the reference character 131 and is similar in geometric configuration to the clip 20. The clip 131 is comprised of two sections C and D, each of which includes a web portion 132, and each of which is provided with a relatively short arm 134 and a relatively long arm 136 connected to opposite ends of the web portions 132. The free ends of the long arms 136 are provided with a transverse hook-shaped end portion 138 which is identical to the hook-shaped end portion 64 provided on the clip 20. Each of the short arms 134 is provided with a transverse groove 140 arranged to cooperably engage the hook-shaped end portion 138 of the arm 136 to fasten the sections C and D together to form the clip 131. The clip 131 may be used in lieu of the clip 20 with either the continuous, elongated strip 18, or the segmented strip 118. Grooved transverse lugs 142 are provided on the clip 131 at the juncture of the web portion 132 with the short arms 134 and grooved transverse lugs 144 are provided on the clip 131 at the juncture of the web portion 132 with the long arms 136. The grooved lugs 142 and 144 are provided to engage the longitudinal edges of the strip 18 or 118 to retain the strips in spaced relation, as described in connection with the clip 20.

FIGS. 8, 9 and 10 illustrate another embodiment of clip which is generally designated by the reference character 150. The clip 150 includes a pair of parallel, spaced arms 152 and 154 which are connected by means of a central portion 156. The free ends of the arms 152 and 154 are provided with transversely extending C-shaped lugs 158, each of which is provided with a groove 160. Similar transversely extending C-shaped lugs 162 are provided on the clip 150 at the juncture between the central portion 156 and the respective arms 152 and 154. The lugs 162 are each provided with a groove 164. The grooves 160 and 164 are arranged to engage the edges of the parallel portions 53 of the grille-forming strip 18 to retain the strips in spaced relation. The arrangement of the clip 150 with a pair of strips 18 can be seen most clearly in FIG. 9. The clips 150 are placed on adjacent, parallel portions 53 of the strip 18, as shown most clearly in FIG. 10. The clips 150 may be assembled thereon by exerting a force on the clip 150 which will tend to spread the lugs 158 and 162 relatively apart, placing the strip 18 therein and releasing the pressure on the clip 150 so that the grooves 160 and 164 will slip over opposed edges of the parallel portions 53 of the strip 18. The clip 150 may also be assembled with the segmented strip 118 by inserting the segment 118a and the segment 118b into the grooves 160-164 from opposite ends of the clip 150 until the hook portion 128 on the segment 118a engages the groove 126 on the end portion 120 of the segment 118b.

It should be apparent from the foregoing description that a grille constructed in accordance with the invention can be quickly and easily assembled without the use of bolts, screws, or other fastening devices, and without the necessity of drilling or punching holes in the various components of the grille 12. It should also be apparent that the various components of the grille 12 can be easily manufactured by production techniques and will require a minimum of time for assembling the grille.

The various embodiments described and illustrated herein are by way of example only and it should be understood that many changes and modifications can be made therein without departing from the spirit of the invention or from the scope of the annexed claims.

What I claim is:

1. An end bracket for supporting grille-forming strips having notched end portions, comprising:
a frame member disposed adjacent the notched end portions of the grille-forming strips;
a supporting member having a surface attached to said frame member and having divergent side surfaces

extending from said surface for connecting the notched end portions of said grille-forming strips to said frame member; and
a plurality of spacer members, each having a web portion and a pair of convergent leg portions arranged to be slidably received by said supporting member, said spacer members being disposed on said supporting member and between adjacent grille-forming strips.

2. An end bracket for supporting grille-forming strips, comprising:

a plurality of grille-forming strips having a notch formed in the end portion thereof, said notch being convergent toward the end of said strip;
a frame member disposed adjacent the end of said strips;
a supporting member having a surface attached to said frame member and having divergent side surfaces extending from said surface, said supporting member being disposed within said notches; and
a plurality of spacer members, each having a web portion and a pair of convergent leg portions arranged to be slidably received by said supporting member, said spacer members being disposed on said supporting member and between adjacent grille-forming strips, whereby said strips will be held in spaced relation.

3. An end bracket for supporting grille-forming strips having notched end portions, comprising:

an elongated frame member disposed adjacent the notched end portions of the grille-forming strips, said frame member having a longitudinally extending bifurcated portion arranged for connecting the notched end portions of the grille-forming strips with said frame member; and

a plurality of spacer members, each having a web portion and a pair of convergent leg portions arranged to be slidably received by said bifurcated portion, said spacer members being disposed on said frame member and between adjacent grille-forming strips.

4. A grille comprising:

a plurality of flat, elongated strips each having a plurality of offset, horizontally and vertically spaced, parallel portions interconnected by a portion inclined with respect to said parallel portions and having each end portion notched, said notches being convergent toward the adjacent end of said strip;

clips positioned between and engaging the parallel portions of said strips, whereby said parallel portions are held in spaced relation;

a frame member disposed adjacent the ends of said strips;

a supporting member having a surface attached to each said frame member and having divergent side surfaces extending from said surface, said supporting members being disposed within said notches; and

a plurality of spacer members, each having a web portion and a pair of convergent leg portions arranged to be slidably received by said supporting member, said spacer members being disposed on said supporting member and between said strips, whereby the ends of said strips are retained on said frame member in spaced relation.

5. The grille of claim 4 wherein said clip includes:

a pair of parallel, spaced end portions;
a central portion extending between and connected with adjacent ends of said spaced end portions; and
means formed on the free end of each end portion and at the juncture of said end portions and central portion forming cooperating pairs of gripping means engaged with said strips to hold said strips in parallel, spaced relation.

6. The grille of claim 4 wherein said clip includes:

a pair of detachably interconnected end sections, said end sections each having a pair of parallel legs and a web portion interconnecting said legs;

releasable latching means formed on the free ends of said legs detachably interlocking said legs together to form said clip; and means at the juncture of said legs with their respective web portion forming cooperating pairs of gripping means engaged with said strips to hold said strips in spaced relation.

7. The grille of claim 6 wherein said releasable latching means includes:

a transversely extending lug formed on the free end of both legs of one said end section; and

means forming a transversely extending groove in the free end of each leg of the other end section, whereby said grooves are arranged to receive said lugs to releasably interconnect said end sections.

8. The grille of claim 6 wherein said releasable latching means includes:

a transversely extending lug formed on the free end of one leg of each end section; and

means forming a transversely extending groove in the free end of the other leg of each end section, whereby said grooves are arranged to receive said lugs to releasably interconnect said end sections.

9. A grille comprising:

a plurality of segmented, flat, elongated strips, each segment having at least two offset, horizontally and vertically spaced, parallel portions interconnected by a portion inclined at an angle with respect to said parallel portions, and having the ends of each segment arranged to be releasably interconnected with the adjacent segment, and each end of each segment being notched, said notches being convergent to the adjacent end of said segment;

5

15

25

30

clips positioned between and engaging the parallel portions of said strips, whereby said parallel portions are held in spaced relation;

a frame member disposed adjacent the ends of said strips;

a supporting member having a surface attached to each said frame member and having divergent side surfaces extending from said surface, said supporting member being disposed within said notches; and

a plurality of spacer members, each having a web portion and a pair of convergent leg portions arranged to be slidably received by said supporting member, said spacer members being disposed on said supporting member and between said strips, whereby the ends of said strip are retained on said frame member in spaced relation.
